(57) **CLAIM**

The ornamental design for a bow, as shown and described.

DESCRIPTION

FIG. 1 is a front perspective view of a bow showing my new design.

FIG. 2 is a rear perspective view thereof.

FIG. 3 is a front view thereof.

FIG. 4 is a rear view thereof.

FIG. 5 is a left view thereof.

FIG. 6 is a right view thereof.

FIG. 7 is a top view thereof; and,

FIG. 8 is a bottom view thereof.

The broken lines shown in the figures represent portions of the bow that form no part of the claimed design.

1 Claim, 8 Drawing Sheets
